United States Patent Office

Des. 231,350

Patented Apr. 16, 1974

231,350

PANEL SECTION OR SIMILAR ARTICLE

Akio Ishida, Littleton, and Alan Paul Webster, Evergreen, Colo., assignors to Johns-Manville Corporation, Greenwood Village, Colo.

Filed Oct. 10, 1972, Ser. No. 296,421

Term of patent 14 years

Int. Cl. D25—01

U.S. Cl. D13—1 J

FIG. 1 is a plan view of the panel section or similar article incorporating the ornamental features of our design;

FIG. 2 is a sectional view taken generally along line 2—2 in FIG. 1; and

FIGS. 3 through 6 are various perspective views of the article of FIG. 1.

We claim:

The ornamental design of a panel section or similar article, as shown.
